CHRISTIAN MUENTENER, OF WEEHAWKEN HEIGHTS, NEW JERSEY.

FABRIC FRAME FOR EMBROIDERING MACHINES.

Application filed May 4, 1925. Serial No. 27,634.

To all whom it may concern:

Be it known that I, CHRISTIAN MUENTENER, a citizen of Switzerland, residing at Weehawken Heights, in the county of Hudson and State of New Jersey, have invented certain new and useful Improvements in Fabric Frames for Embroidering Machines, of which the following is a specification.

This invention relates to fabric frames for 10 embroidery machines of the Shiffli or similar type.

When it is desired on this type of machine having fabric frames of the usual construction to produce embroidery for individual pieces of goods, as, for instance, handkerchiefs, stockings or the like, a single continuous piece of fabric must be used, which is spanned over the entire length of the fabric frame and after the work is finished, the 20 fabric must be cut up into individual pieces or strips, each containing the embroidered design, and adapted to be separately attached to an individual article or garment for which it was intended. It is obvious 25 that such method not only consumes much time in the cutting up of the embroidered fabric to individual pieces and in the sewing of the same to the articles, but also causes much waste of material, since enough material for stitching or the formation of seams 30 must be left on each strip or piece around the embroidery, so as not to encroach on the embroidered design. There is also the objection that the article having the embroidery subsequently inserted or sewed on to it is 35 rendered unattractive.

But apart from the afore-named objections, there is still the following objection: To permit the individual embroidery designs to be spaced apart sufficiently, so that the fabric may be subsequently cut up into individual strips or pieces, those needles, which are located at the intervals between each two adjacent designs, must be removed 45 from the machine prior to the operation, as otherwise they would pierce the fabric at the intervals between adjacent designs and leave marks in the fabric. The number of needles to be removed from the machine will 50 vary with the width of the designs to be embroidered. Therefore, with each different design, a new rearrangement of the needles is required, which, when considering that there are hundreds of needles in a machine, 55 will occasion additional loss of time and labor.

To obviate all these drawbacks, it is the main object of my invention to provide for machines of the Shiffli type or the like a special device, which will be suitable for the simultaneous production of embroidery on individual pieces or strips of fabric or on individual articles directly. I accomplish this object by providing a frame, which, in lieu of the ordinary fabric frame, can be 60 easily and rapidly attached to any existing embroidery machine of the type mentioned and which is divided into individual compartments or stalls arranged in a continuous horizontal row along the entire length 65 of the machine. Each stall of this frame is adapted to receive and removably support a tambour frame, which, similar to that used for hand embroidery, is composed of two hoop-shaped interengaging parts between 70 which the fabric or article to be embroidered is spanned. To enable the spanning of the individual pieces of fabric or articles between the hoops of the tambour, without undue stretching thereof, I employ a base 75 formed with a block having centering means and projecting from the base, said block being of a configuration and size to correspond with that of the inner hoop, so that, after slipping the inner hoop over said block, 80 placing the piece of material flat over them and slipping the outer hoop over the material and the inner hoop, the material will become frictionally engaged between the inner and outer hoops and spanned. 85

Another object of this invention is to provide means for securely holding the removable tambour frames in operative position within the individual stalls and which will permit these frames to easily and quickly 90 be exchanged.

To produce embroidery or articles which in length or breadth or both are larger than the tambour frames, the parts of the article extending beyond the tambour hoop must 100 be folded up and means are required to retain these parts in folded condition, during the operation, in order to prevent them from spreading over the adjacent tambour frames. It is not possible to use pins for the purpose, since pins always leave perceptible marks, particularly with certain kinds of materials. It is, therefore, another object of my invention to provide suitable clamping means for this purpose. 105

My invention will be more fully understood from the detailed description thereof 110

by reference to the accompanying drawing, in which similar reference characters denote corresponding parts and in which Fig. 1 is a front view of my device shown applied to an embroidering machine of which only so much is shown as is necessary to make my invention clear; Fig. 2 is a vertical section on line 2—2 of Fig. 1; Fig. 3 is a cross-section on line 3—3 of Fig. 1; Fig. 4 is a perspective view of the tambour frame illustrating the mode of spanning the material between the two hoops thereof on the special base used therefor; Fig. 5 is a vertical section of the tambour frame and base with the material spanned between the two hoops of said frame; and Fig. 6 is a section of the tambour frame removed from the base with the material spanned in it and with the unspanned parts thereof folded up and clamped to the tambour frame.

Referring to the drawing, *a* and *b* indicate parts of an embroidering machine of the Shiffli or similar type, *a* being in form of a vertical rod or post and *b* an L-shaped rail extending longitudinally of the machine and both serving for the suspension of the fabric frame.

My new device comprises a main frame 10, which, in lieu of the usual fabric frame, is adapted to be vertically supported in the machine and which extends the entire length of the latter. The same is composed of two longitudinal bars 11, one on top and the other at the bottom, and a plurality of parallel cross bars 12 fixed in said longitudinal bars. In the present example, the cross bars 12 are in form of comparatively thin metal strips bent longitudinally upon themselves. The ends of these bars 12 are adapted to engage transversal recesses 11' made in the bars 11 and to be suitably fastened thereto, as at 11². The strips 12 divide the frame 10 into a plurality of separated compartments or stalls 13 arranged in a continuous horizontal row extending over the entire length of the embroidering machine. For the attachment of the frame to the machine, the lower bar 11 may be formed with a few pins 14 and the rail *b* with corresponding apertures *b'* to engage the same, while the upper bar 11 may be clamped at intervals in position by suitable clamps 15 provided on arms 16 movably borne on rods *a* of which only one is shown in Fig. 1.

Each individual articles *c* or pieces of material, such as handkerchiefs, gloves or the like to be embroidered are adapted to be spanned in individual tambour frames to be supported in the stalls of the frame 10. Each individual tambour frame is composed of two hoop-shaped members 16, 17 substantially of rectangular shape, capable of being slipped one over the other like the hoops of an ordinary hand embroidery tambour. Each of these hoops is made of compara-

tively thin metal strips doubled upon themselves and which in width correspond substantially with the strips 12. In width, the outer hoop is such as to fit more or less snugly in a stall 13 of the frame 10. The outer hoop has attached to its upper and lower walls U-shaped members 16', 16² made of similar strips to those of the main body of the hoop. Extending through perforations 12^a in the strips 12 of the main frame longitudinally of the frame 10, is an upper rod 18 and two adjacent lower rods 19, 20, all of said rods being parallel to one another. The U-shaped extensions or members 16' are provided with hooks 16^a or the like to engage the bar 18, and the members 16² with fingers 16^b to bear against the front face of the upper one of the two lower rods 19, 20. These outer hoops 16 can be positioned in the stalls 13 of the frame 10 by hooking their upper extensions 16^a to the rod 18 and placing their fingers 16^b against the rod 19.

Slidably mounted on the lower rods 19, 20, one for each tambour frame, is a member 21, which is formed with a part 21' adapted, when the slide is moved, say to the right of a stall, to overlap the finger 16^b of the hoop 16 and thereby lock the tambour frame in operative position.

To facilitate the spanning of the articles or pieces of material *c* in the tambour frames, I employ a base block, which may consist of a base plate 22 from the upper face of which projects a block 23 of a size and shape conforming with the inner loop 17, so that the latter can be freely slipped over said block as shown in Fig. 4. To span the material *c*, the latter is placed flat against the upper face of the block 23, after the hoop 17 has been slipped over it, and the outer hoop 16 is then slipped over the inner hoop to frictionally engage the material *c* between itself and the latter and to draw it sufficiently taut for the embroidering operation without, however, unduly stretching it. The block has two or more centering pins 24 projecting therefrom, whereby the articles to be embroidered may be properly centered and spanned uniformly in the different tambour frames.

After the material *c* has been thus spanned, the two hoops 16, 17 are removed from the block 23 and placed into a stall 13 of the frame 10 in the afore-described manner with the material extending over the inner or rear edges of the hoops and projecting forwardly from the spaces between the two hoops. The excess or unspanned parts of the material are then gathered or rolled up, as at *c'*, in Figs 6, to be out of the way of the adjoining stall and are clamped in the folded condition by a U-shaped spring clamp 25 or the like. The spindles 19 and 20 may be lowered

or raised to enable the attachment of tambour frames of different length. To this end, the members 12 may each have a plurality of apertures 12^a in which the rods 19, 20 can be mounted and which are arranged perpendicularly to the bars 12 and spaced uniformly, the apertures 12^a in the different members 12 being in alignment with one another. The rods 19, 20 may 10 be secured against lateral movement by pins or the like 26 borne in their extreme ends.

For the purpose of permitting the use of tambour frames of different width, the longitudinal bars 11 may have a great number 15 of closely arranged recesses 11^a, as shown in Fig. 1, whereby the width of the stalls can be made variable.

It will be obvious that with my new device it is possible to produce embroidery 20 by an embroidering machine of the Shiffli type or the like directly on articles of different size and of any kind of material, without undue stretching of the latter.

What I claim is:—

25 1. In an embroidering machine of the character described, a device consisting of a single frame adapted to extend vertically the entire length of the machine and divided longitudinally by cross members into a plurality of stalls or compartments, a set of parallel rods extending longitudinally of the machine and borne in said cross members, sets of individual tambour frames adapted to snugly fit in said stalls, each 30 set comprising an outer rectangular frame formed with longitudinal end extensions adapted at their opposite ends to removably engage said parallel rods, and an inner rectangular frame capable of frictionally engaging a piece of material between itself and said outer frame, and a locking member for locking said outer frame of each set 35 in operative position.

2. In an embroidering machine of the character described, a device consisting of 45 a single frame adapted to extend vertically the entire length of the machine and divided longitudinally by cross members into a plurality of stalls or compartments, a set of parallel rods extending longitudinally of the machine and adjustably borne in said cross members, sets of individual tambour frames adapted to snugly fit in said stalls, each set comprising an outer rectangular frame formed with longitudinal end extensions 50 adapted at their opposite ends to removably engage said parallel rods, and an inner rectangular frame capable of frictionally engaging a piece of material between itself and said outer frame, and a locking member for locking said outer frame of each set 55 in operative position.

3. In an embroidering machine of the character described, a device consisting of 60 a single frame adapted to extend vertically the entire length of the machine and divided longitudinally by perforated cross members into a plurality of stalls or compartments, a set of parallel rods extending longitudinally of the machine and adjustably borne in the perforations of said cross members, sets of individual tambour frames 65 adapted to snugly fit in said stalls, each set comprising an outer rectangular frame formed with longitudinal end extensions 70 adapted at their opposite ends to removably engage said parallel rods, and an inner rectangular frame capable of frictionally engaging a piece of material between itself and said outer frame, and a locking member for locking said outer frame of each set 75 in operative position.

In testimony whereof I affix my signature.

CHRISTIAN MUENTENER.
